UNITED STATES PATENT OFFICE.

ISAAC T. MONTROSS, OF PEEKSKILL, NEW YORK.

DESIGN FOR A RANGE.

SPECIFICATION forming part of Design No. 12,315, dated June 14, 1881.

Application filed May 2, 1881. Term of patent 3½ years.

To all whom it may concern:

Be it known that I, ISAAC T. MONTROSS, a citizen of the United States, residing at Peekskill, in the county of Westchester and State of New York, have invented and produced a new and original Design for Ranges, of which the following is a specification, reference being had to the accompanying drawing, forming a part thereof.

- 10 o The figure in the drawing is a perspective view of a range embodying my design, which is applied to the doors of ranges as follows:

15 The oven-door A of the range has a central, or an approximately central, raised figure, B, which consists of a center field or panel, b, that is provided for any appropriate name or design indicative of the class or character or name of the range—such, for example, as the name "Bon Ton" or the name of the manufacturers of the range—and a continuous raised border around said panel, consisting, essentially, of the bottom straight ridge, C, the curved side ridges, D D, and the top ridge, E, which is diversified by the central curved or 25 arched portion, e, and by the two inclined end portions, f f, there being in this top portion of the said border two straight horizontal ridges intermediate of the arch e and the inclined ends f f.

30 o Upon the range-door, at the sides of the figure B, just described, are the figures H, representing scroll-work, the upper portions of which connect by a border, I. This border has the two inclined edges, L L, which meet, 35 so as to form an arch over the figure B, heretofore described. At the point where these inclined edges intersect there is a raised pendant, e', overhanging the arch e of the center figure upon the door. The inclined edge-lines

40 o M M, that run from the outer terminal points of the inclined edges L to a bead or representation of molding, m, around the door, tend to give the border I the appearance of a canopy over the center figure, B.

45 o The grate and fire-door N is ornamented by a border, n, constituting an arch, having at the lower portion of its sides the scrolls P P, and extending down from its top the pendant

50 o R. Below this arch is a scroll, S, surmounted by a ring, T, having a radial projection or

knob, U, pointing upward toward the top of the arch. The space that is surrounded by the arch and the scroll can be used for any desired name, number, or configuration deemed desirable.

55 The horizontal shelf W at the rear of the range is ornamented by a number of slots or openings, which represent scroll-work, some of the openings being semicircular slots, others angular openings, and others being made in the form of trefoils, as clearly illustrated in the drawing.

At the four corners of the range are the cylindrical columns X X X X, there being one column for each corner. These four columns 65 each end from the base to the top plate of the range, but two of the said columns being shown in the drawing.

At the right and left ends of the range will be found a raised panel, Y, bearing a facsimile of the design on the oven-door A, before described, and which need not, therefore, be further illustrated, the outlines of one of these panels being indicated at one end of the range.

70 A horizontal bead, Z, runs along the side of the stove, below the oven-door, said bead commencing at one of the upright columns and extending to the fire and grate door.

75 What I claim is—

80 1. The design herein shown and described for a range, the oven-door of which is provided with a panel bounded by the straight raised bottom border, C, the side borders, D, and the top border, E, which is diversified by an arch and by horizontal and inclined portions.

85 2. The design herein shown and described for a range, the oven-door of which is provided with a panel surrounded by a raised border, the scrolls H at the sides thereof, and the border I, having its lower edges inclined and meeting centrally at the pendant e'.

90 3. The design herein shown and described for a range, the fire-door of which is provided with an arch-shaped border, n, having scroll-shaped sides, and the pendant R at the top of the arch.

95 4. The design herein shown and described for a range, the fire-door of which is provided

with the arch-shaped panel border *n*, having scroll-shaped sides *P*, the pendant *R* at the top of the arch, the scroll *S* below the arch, and the ring *T*, arranged above the said scroll 5 and having the radial knob *U*.

5. The design herein shown and described for a range, the doors of which are provided with panels surrounded by ornamental borders, and the corners of the range having each 10 a cylindrical upright column, *X*.

In testimony whereof I have hereunto set my hand in the presence of the subscribing witnesses.

ISAAC T. MONTROSS.
